(57) **CLAIM**

The ornamental design for a semiconductor probe pin as shown and described.

DESCRIPTION

FIG. 1 is a perspective view of a semiconductor probe pin showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof; and,

FIG. 8 is an enlarged partial view indicated in FIG. 4 thereof. The dot-dash broken line indicates the boundary of the enlarged partial view and forms no part of the claimed design.
